[57] CLAIM

The ornamental design for a multi-tined digging tooth, as shown and described.

DESCRIPTION

FIG. 1 is a perspective view of a multi-tined digging tooth showing one embodiment of our new design;

FIG. 2 is a top plan view of the multi-tined digging tooth illustrated in FIG. 1;

FIG. 3 is a bottom plan view thereof;

FIG. 4 is a left side view thereof with the right side view being a mirror image thereof;

FIG. 5 is a rear elevational view thereof;

FIG. 6 is a front elevational view thereof;

FIG. 7 is a perspective view of a multi-tined digging tooth showing a second embodiment of our new design;

FIG. 8 is a top plan view of the multi-tined digging tooth illustrated in FIG. 7;

FIG. 9 is a bottom plan view thereof;

FIG. 10 is a left side view thereof with the right side view being a mirror image thereof;

FIG. 11 is rear elevational view thereof; and,

FIG. 12 is a front elevational view thereof.

FIGS. 2 through 6 and 8 through 12 are shown on an enlarged scale relative to FIGS. 1 and 7, respectively.
